UNITED STATES PATENT OFFICE.

ISAIAH L. ROBERTS, OF BROOKLYN, NEW YORK, ASSIGNOR OF ONE-THIRD
TO EDWARD N. DICKERSON, OF NEW YORK, N. Y.

CURRENT AND PROPULSION WHEEL.

SPECIFICATION forming part of Letters Patent No. 747,775, dated December 22, 1903.

Application filed July 27, 1897. Serial No. 646,079. (No model.)

To all whom it may concern:

Be it known that I, ISAIAH L. ROBERTS, of Brooklyn, county of Kings, State of New York, have invented a new and useful Improvement 5 in Current and Propulsion Wheels, of which the following is a specification.

Heretofore current and propulsion wheels have been made with plain or flat paddles; but these have been of low efficiency and often 10 impractical for use in cold climates, owing to the freezing of water on the same while in motion. By my invention the efficiency is much increased, and the difficulty of ice forming on the wheel is overcome.

15 In the drawings I have illustrated a construction embodying my invention, in which—

Figure 1 is a longitudinal section through the wheel, the shafts, and supports. Fig. 2 20 is a section along lines 2 2 of Fig. 1, certain parts being shown in full. Fig. 3 is a plan view of a paddle. Fig. 4 is a transverse section of a paddle. Fig. 5 is a longitudinal section along lines 5 5 of Fig. 4, and Fig. 6 illustrates the method of staggering the paddles.

Like numerals of reference refer to like parts throughout the several views of the drawings.

Referring to said drawings in detail, 1 1 30 represents the supports or piers for the journals of the wheel-shaft. On each of these piers is a hydraulic cylinder 2, in which works a ram 3, provided at its upper end with the journal-piece 4, having a bushing 5, in which 35 is journaled a hollow shaft 6, on which are mounted the paddles. The shaft 6 is shown as made in sections to adapt it to span a stream of considerable width.

A series of paddles 8 are mounted on spokes 40 9, said spokes being made hollow and communicating through an opening 10 with the interior of the hollow shaft. Any suitable form of connection may be availed of for securing the paddles to the shaft, and in the drawings 45 I have shown the spokes as provided with flanges 11 for bolting the same to the hollow shaft, a packing-ring 12 being shown for the purpose of obtaining a fluid-tight connection.

The paddles 8 are preferably made of 50 sheet metal of sufficient strength to withstand the impact of the current, and each of said

paddles consists of a compartment the operative face of which, 13, is composed of two concave surfaces, each surface being substantially a quarter-section of a cylinder. These 55 two surfaces meet and project forward at the middle portion of the paddle, which impinges against or receives the impact of the water accordingly as the wheel may be used as a driven or a drive wheel. The advantage of employing 60 a concave surface approximating a portion of a cylinder is that when the current strikes the curved surface it is immediately diverted at about a right angle. This is true when one edge of the curved surface is directly in the plane 65 of the current. Hence in the case of two concave surfaces each substantially a quarter-section of a cylinder and so joined together that their apex or wedge-like edge is presented to the impact of the current the current will 70 be deflected or diverted ninety degrees from the direction of impact, thus obtaining the greatest possible efficiency. Any departure from a curve which will not describe a true circle and a curve greater than a quarter- 75 curve prevents the obtaining of the maximum efficiency. In the case of the ordinary bucket, scoop, or flat surface in paddles the current striking it backs upon the surface and forms a cone the angle of which is about forty-five 80 degrees. This cone of water is practically a solid to passing water, around which the water passes as though the surface was a polished metal cone having its apex pointed to the direction of impact. Hence only half as 85 much energy is obtained when compared to my arrangement. The inclosed receptacle constituting the paddle is in communication with the spokes 9 through perforations 14, and hot air is circulated through the hollow 90 shaft and spokes to each of the paddles mounted on said shaft, passing out through escape-pipes 15, which are secured to the spokes by a collar 16, and discharge into a hood 17, which prevents the dripping of water 95 into the tubes 15, the source of hot-air supply or steam or other heating medium being, as shown in the drawings, by means of a tube 18.

The hydraulic rams constitute a means for 100 raising or lowering the shaft corresponding, as the same may be desired to adapt the

wheel for different heights of the stream and also for the purpose of regulating the speed of the wheel according to the amount of the load on the wheel. These hydraulic rams 5 may be automatically connected with a governing device, so that an increase of speed in the wheel will cause an admission of water to the hydraulic cylinder to raise the wheel, and thus decrease the speed. I have discovered that by making the operative face of my paddles of the two concave surfaces described and placing those concave surfaces at an angle to the direction of the stream of, say, forty-five degrees I obtain a maximum 15 efficiency, each concave surface forming a balancing and supporting resistance for the other of the same paddle. The rear face of the paddle is comprised of one or more convex plates 19, which approximate the curvature of the front plates and serve to strengthen and support the front plates which constitute the operative face of the paddles.

A perforated diaphragm 20 is placed in the shaft 6, which diaphragm while it permits 25 most of the hot air to pass through the spokes and paddles and be discharged through the tubes 15 yet permits of sufficient hot air or steam reaching the end of the shaft.

Where I mount the series of spokes in different vertical planes I stagger them, so that the water impinging against the face of the first paddle will be thrown off upon the second paddle, which then diverts the stream in two directions at right angles to the direction 35 of the stream-current. This method of staggering is shown in Fig. 6.

Of course the paddles here described and shown may be made solid and no circulation of heating fluid be availed of in cases where 40 the temperature of the climate does not necessitate any artificial means for heating the paddles to prevent the accumulation of ice, the essential feature being the double concave converging surfaces of the paddles. It 45 will also be evident that the invention may be applied to a stationary wheel driven by the current and operating a plant or to a paddle-wheel of a vessel for the purpose of propelling the same.

50 What is claimed as new is—

1. The combination in a partially-submerged paddle-wheel, of a shaft, a series of spokes carried by said shaft, and a paddle carried by each spoke, said paddle consisting

55 of a concave surface, which is a section of a cylinder having one of its edges turned to the direction of impact.

2. The combination in a partially-submerged paddle-wheel, of a shaft, a series of 60 spokes carried by said shaft, and a paddle carried by each spoke, said paddle consisting of a concave surface which is a quarter-section of a cylinder, said surface having one of its edges turned to the direction of impact.

65 3. The combination in a partially-submerged paddle-wheel, of a shaft, a series of spokes carried by said shaft, and a paddle

carried by each spoke, said paddle each consisting of two concave surfaces oppositely arranged, each having an edge meeting to form 70 a wedge which is in the direction of the impact, and each of said concave surfaces being a quarter-section of a cylinder.

4. The combination in a paddle-wheel, of a hollow shaft through which a heating medium is passed, a series of hollow spokes carried by said shafts and in communication with and adapted to receive said heating medium from said shafts, and a receptacle carried by each spoke and in communication 80 therewith and also adapted to receive said heating medium, said receptacle constituting a paddle and being provided with opposite, concaved impact surfaces.

5. In a paddle-wheel, a shaft provided with 85 a series of tubular spokes, and hollow paddles carried by the spokes, the spokes extending into the paddles and constituting conduits for a heating medium and having outlets in 90 the paddle for the escape of such heating medium.

6. In a paddle-wheel, a shaft provided with a series of tubular spokes, hollow paddles carried by the spokes, the spokes extending into the paddles and constituting conduits for a 95 heating medium and having outlets in the paddle for the escape of such heating medium, and discharge-pipes leading from the paddles, for the heating medium.

7. In a paddle-wheel, a shaft provided with 100 a series of tubular spokes, hollow paddles carried by the spokes, the spokes extending into the paddles and constituting conduits for a heating medium and having outlets in the paddles for the escape of such heating medium, 105 discharge-pipes leading from the paddles for the heating medium, and means for preventing the entrance of water through which the paddle moves, into the outlets of the discharge-pipes.

8. In a paddle-wheel, a shaft provided with 110 a series of tubular spokes, hollow paddles carried by the spokes, the spokes serving to conduct a heating medium into the hollow paddles, discharge-pipes for the heating medium, 115 leading from the paddles and connected with the spokes, and hoods carried by the spokes, covering the outlets of the discharge-pipes and preventing the entrance of the water through which the paddle moves, into said 120 discharge-pipes.

9. In a paddle-wheel, a shaft and a hollow paddle connected with said shaft, means for delivering a heating medium into said paddle, a discharge-conduit for the heating medium from said hollow paddle, and means for preventing the water from obstructing the exit of said discharge-conduit.

10. In a paddle-wheel, a shaft and a hollow paddle connected with said shaft, means for 130 delivering a heating medium into said paddle, a discharge-conduit for the heating medium from said hollow paddle, and a hood surrounding the exit of the discharge-conduit

to obstruct the entrance of water into said exit.

11. In a paddle-wheel, a shaft provided with a series of tubular spokes, hollow paddles carried by the spokes, the spokes serving to deliver a heating medium into said hollow paddles, discharge-pipes for the heating medium connected with and leading from the paddles and connected with the respective spokes, and means upon said spokes for obstructing

the exit of the discharge-pipes against the admission of water thereinto.

In testimony whereof I have signed my name to this specification in the presence of two subscribing witnesses.
